UNITED STATES PATENT OFFICE.

JOSEPH O. HÉBERT, OF GRAND RAPIDS, WISCONSIN.

PENCIL-HOLDER FOR SLATE-FRAMES.

SPECIFICATION forming part of Letters Patent No. 416,728, dated December 10, 1889.

Application filed August 29, 1889. Serial No. 322,308. (No model.)

To all whom it may concern:

Be it known that I, JOSEPH O. HÉBERT, a citizen of the United States, residing at Grand Rapids, in the county of Wood and State of Wisconsin, have invented a new and useful Pencil-Holder, of which the following is a specification.

The invention relates to improvements in pencil-holders.

10 The object of the present invention is to provide a holder of simple and inexpensive construction designed to receive a pencil and hold the same when not in use, and adapted to be readily secured to a slate and held in place by the cover thereof.

15 The invention consists in the construction and novel combination and arrangement of parts hereinafter fully described, illustrated in the accompanying drawings, and pointed 20 out in the claim hereto appended.

In the drawings, Figure 1 is a perspective view of a slate provided with a pencil-holder constructed in accordance with this invention.

25 Fig. 2 is a central vertical longitudinal sectional view of a portion of the slate-frame. Fig. 3 is a horizontal longitudinal sectional view. Fig. 4 is a transverse sectional view of the same. Fig. 5 is a central longitudinal sectional view of a portion of the slate-frame, 30 showing both ends of the holder open.

Referring by letter to the accompanying drawings, A designates a slate-frame constructed in the ordinary manner, and having one of its sides, preferably the top piece a, 35 provided with a holder B, which is secured in place by the cord C, that binds a slate-cover D around the edges of the slate-frame A, and the pencil-holder B, the cord being passed through perforations a' and over the frame 40 around the cover.

The pencil-holder B may be glued or similarly secured to the slate-frame; and it con-

sists of a strip of light material, preferably of some wood to match the slate-frame A, and is provided with a longitudinal bore b, which 45 receives a pencil E and securely holds it in a convenient position. The bore b, which is slightly larger than the diameter of a slate-pencil, may extend entirely through the strip, or may have one end closed, as desired, and 50 it is provided with a long flat spring F, which has one of its ends secured to the bottom of the bore. The spring extends nearly the entire length of the bore, and is slightly curved throughout its length, and it engages the pencil and presses the latter against the sides of the bore b, and thereby securely retains it in the holder against accidental displacement.

The bore b may be made in the slate-frame A, and I desire it to be understood that I do 60 not limit myself to the precise details of construction herein shown and described, as I may, without departing from the spirit of the invention, make various minor changes therein.

65 From the foregoing description and the accompanying drawings the construction, operation, and advantages of the invention will readily be understood.

70 What I claim is—

The combination of a slate-frame provided with a series of perforations, a strip having a longitudinal bore to receive a pencil, and a cord passing through the perforations and over the strip, whereby the latter is secured 75 in place, substantially as described.

In testimony that I claim the foregoing as my own I have hereto affixed my signature in presence of two witnesses.

JOSEPH O. HÉBERT.
